UNITED STATES PATENT OFFICE.

JOHN HARRIS, OF SHEFFIELD, ENGLAND, AND DAVID HIBBERT THOMAS, OF MORRISTON, WALES.

SULFURIC-ACID CHAMBER.

1,203,615.

Specification of Letters Patent.

Patented Nov. 7, 1916.

Application filed March 27, 1916. Serial No. 86,999.

To all whom it may concern:

Be it known that we, JOHN HARRIS, metallurgist, and DAVID HIBBERT THOMAS, chemist, subjects of the King of England, residing, respectively, at Sheffield, in England, and at Morriston, in Wales, have invented certain new and useful Improvements in or Relating to Sulfuric-Acid Chambers; and we declare the following to be a full, clear, and exact description of the same.

This invention relates to sulfuric acid chambers, its object being to provide improvements in the construction of the frame or structure supporting it and in the means for attaching the chamber curtain thereto, these means being such that they are easily accessible for repairs without risk of damage to the chamber.

In the accompanying drawings:—Figure 1 is an elevation of a sulfuric acid chamber and its surrounding frame or structure, according to this invention. Fig. 2 is a plan of Fig. 1. Fig. 3 is an enlarged elevation showing means for attaching the curtain to the frame. Fig. 4 is a similar view to Fig. 3 showing a modification. Fig. 5 is a plan of Fig. 4. Fig. 6 is an enlarged sectional elevation of an upper corner of the chamber and frame shown in Figs. 1 and 2.

Like reference figures indicate like parts throughout the drawings.

The frame or structure which surrounds and supports the leaden chamber comprises vertical pillars or girders 1 and horizontal girders 2 suitably bolted or riveted together and, if necessary, strengthened by stays, tie rods or the like. The curtain 3 is suspended from the girders 2 being attached thereto at the desired number of points. For each point of attachment a hook 4 (Figs. 3, 4 and 5) is pivoted to the curtain 3, conveniently by a strip of lead 5 which is "burnt" to the curtain in the usual manner, the hook being preferably but not necessarily U-shaped as shown in Fig. 5. Each of the hooks 4 is caused to engage one of the girders 2 or a part carried thereby. In the preferred construction a second hook-like member 6 engages the girder 2 while the hook 4 engages the member 6. In order to prevent the curtain 3 from coming into contact with the frame a block or the like 7 is forced between the curtain and the frame at each point of attachment, the block being in compression and serving if desired to lock the hook 4 and

the member 6 to the girder as well as to insure the hook 4 taking its share of the weight of the curtain 3. In order thus to lock the parts together one end of the block is shaped to fit the space between the lower rail of the member 6 and the horizontal web of the girder, this end of the block being first placed in position as shown in chain lines in Fig. 4 and the block being then forced into a horizontal position. When the member 6 is not used the block 7 would be situated between the horizontal web of the girder and a horizontal bar on, or other convenient part of, the hook 4. With this attachment it will be seen that if a rent or tear should appear in the curtain adjacent to a point of attachment (which is the place where rents usually do occur first) it will be easily accessible for repair and it will be unnecessary to detach any of the hooks 4 save the one in proximity to the damage. In a mode of attachment largely in use heretofore the curtain was secured to beams extending the whole length and breadth of the curtain, so that a number of points of attachment had to be loosened to gain access to one, thus throwing considerable extra weight on the other points of attachment which often led to further damage to the curtain. With means of attachment according to this invention, however, such risk is avoided. In addition to their other functions the blocks 7 hold the curtain 3 away from contact with the metal structure and thus also permit air to circulate about the exterior surface of the curtain.

The upper ends of the curtain may be attached to one of the girders 2 by any known means such as by bolts and nuts as indicated at 8 in Fig. 6, although the special means hereinbefore described and illustrated in Figs. 3, 4 and 5 may be employed here also if desired.

The edges of the roof 9 are "burnt" to the upper portions of the curtain as usual, and the roof is suspended from bars 10 by hooks 11 pivoted to the roof in a manner similar to that employed for connecting the hooks 4 to the curtain. These bars or rods 10 from which the roof 9 of the chamber is suspended are radially arranged between a central ring or disk 12 and a suitable part of the frame or structure such as the vertical pillars 1. If desired the outer ends of these radial bars may be attached to an outer ring suit-

ably supported by the frame or structure. In the construction illustrated the radial bars 10 are in compression; they may however be arranged to be in tension, or some may be in tension and others in compression, radial tension bars 13 being also shown in Figs. 1, 2 and 6. Some of the bars 10 and 13 have been omitted from Fig. 1 for the sake of clearness. The aperture within the ring 12 10 may be utilized to take a pipe or flue 14 for the passage of gases leaving (or entering) the chamber. Although this form of construction comprising the radial roof rods is most applicable to a cylindrical chamber, it 15 may be used for square and other rectangular chambers.

Drainage apertures are made in the part 20 of the curtain 3 which projects above the roof 9 and thus the dome- or arch-like form of the roof will be effective in preventing rain water from remaining on the roof and from adding unnecessary weight to be supported in cases where the roof 9 is not covered in.

25 The roof 9 and the whole or a part of the curtain 3 may be water-cooled, and the water therefrom may be led to the Glover tower coolers and be utilized there.

What we claim and desire to secure by Letters Patent is:—

1. In a structure for supporting a sulfuric acid chamber the combination with pillars around the chamber, of a central member above the chamber roof supported from the 35 said pillars by radial bars, substantially as set forth.

2. In a structure for supporting a sulfuric acid chamber the combination with pillars around the chamber, of a central member above the chamber roof supported from the 40 said pillars by radial tension bars, substantially as set forth.

3. In a structure for supporting a sulfuric acid chamber the combination with pillars around the chamber, of a central member above the chamber roof supported from the 45 said pillars by radial compression bars, substantially as set forth.

4. In a structure for supporting a sulfuric acid chamber the combination with pillars around the chamber, of a central member above the chamber roof supported from the 50

said pillars by radial bars some of which are in tension and some in compression substantially as set forth.

5. In a structure for supporting a sulfuric acid chamber the combination with pillars around the chamber, of a central member above the chamber roof supported from the 55 said pillars by radial bars some of which are in tension and some in compression and a flue passing through the central body, substantially as set forth.

6. In a structure for supporting a sulfuric acid chamber the combination with pillars around the chamber, of a central member above the chamber roof, supported from the 60 said pillars by radial bars and a ring taking stresses transmitted by the radial bars substantially as set forth.

7. The combination with the roof and curtain of a sulfuric acid chamber, of a supporting frame comprising a series of pillars arranged around the chamber and means connecting said pillars, means for suspending the roof of the chamber from said frame, a series of hooks each pivotally connected to the chamber curtain and engaging said frame, and a block in compression between said curtain and frame adjacent each of said 75 hooks.

8. The combination with the roof and curtain of a sulfuric acid chamber, of a supporting frame comprising a series of pillars arranged around the chamber and means connecting said pillars, means for suspending the roof of the chamber from said frame, and means for connecting the chamber curtain and frame comprising a series of hooks pivotally attached to the curtain and engaging the frame, and blocks in compression between the curtain and frame and each acting to lock one of the hooks to the frame.

In testimony whereof we have signed our names to this specification in the presence of two subscribing witnesses.

JOHN HARRIS.
DAVID HIBBERT THOMAS.
